UNITED STATES PATENT OFFICE.

EDWARD E. MASTON, OF CHICAGO, ILLINOIS, ASSIGNOR TO MID-WEST BOX COMPANY, OF CHICAGO, ILLINOIS, A CORPORATION OF INDIANA.

BOTTLE WRAPPER.

Application filed February 27, 1922. Serial No. 539,351.

The invention relates to bottle wrappers.

One object of the invention is to provide an improved wrapper for bottles and the like in which a fly-sheet and a corrugated cushion sheet are combined with flaps which are adapted to form end closures for the package. In wrappers of this type, it has heretofore been common practice to use corrugated end closing sheets which were separate from the wrapper and this retarded the packaging of the goods, because the end pieces had to be separately handled. By forming the flaps on the corrugated liner, the articles can be wrapped with greater facility.

A further object of the invention is to provide an improved wrapper for bottles and the like which is simple in construction, can be produced at a low cost and serves to efficiently protect an article from breakage.

The invention consists in the several novel features hereinafter set forth and more particularly defined by claims at the conclusion hereof.

In the drawings: Fig. 1 is a plan of a wrapper embodying the invention. Fig. 2 is a plan section on line 2-2 of Fig. 3, the wrapper being shown folded to fit around a bottle before the margins of the fly-sheet have been folded to close the ends of the package. Fig. 3 is a vertical section on line 3-3 of Fig. 2. Fig. 4 is a side elevation.

The invention is exemplified in a wrapper comprising a fly sheet 6, usually of stout flexible paper, adapted to form an outer covering and a sheet of single-faced corrugated board which consisted of a corrugated sheet 7 and a liner 7' glued in usual manner to the back thereof and secured to the fly sheet by a suitable adhesive on lines 8. The corrugated sheet 7 and its liner each comprise a main or body portion 9 cut to a height corresponding to the height of the bottle or article to be wrapped and of sufficient width to extend around or encircle the bottle, a pair of bottom flaps 10 and a pair of top flaps 11 which are integrally formed with the body 9. The corrugated sheet is creased on the lines of junction between the flaps and the body portion to render the flaps foldable transversely to their length. The flaps are semi-circular and the pairs at the top and bottom are adapted to form, when folded inwardly on said lines, end or top and bottom protecting walls for

the bottle. That is to say, when the semi-circular flaps 10 of the bottom are folded inwardly, their straight margins will meet to form a bottom protection for the bottle and the flaps 11 will perform a similar function for the top of the bottle. The fly-sheet 6 has one of its ends coterminous with the corrugated sheet 7 and its other end is extended beyond the corrugated sheet to form an extension 12 which is adapted to overlap the other end and is usually provided with an adhesive for securing it around the bottle or article. The top and bottom margins 13 and 14 of the fly-sheet are extended beyond the margins of the body to form flexible flaps or portions which are folded inwardly upon the outer sides of the flaps 10 and 11 respectively to form an outer covering or seal for the ends of the package and may be secured in closed position by an adhesive or label if desired.

The invention exemplifies a wrapper for bottles and other articles composed of a fly-sheet and a corrugated cushioning sheet or liner which are secured together and corrugated end flaps which are connected or integral with the cushioning sheet. As a result of providing a wrapper of this character, the work of wrapping is greatly facilitated over wrappers in which separate sheets of corrugated board are used to protect the ends of the bottle or article.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. A wrapper for bottles and the like comprising a fly-sheet adapted to extend around a bottle or other article, a cushion board comprising a corrugated sheet and a facing sheet on one side thereof secured to the fly sheet, the corrugated and facing sheets having integral portions respectively to extend around the bottle or article, and corrugated end flaps integrally formed with the corrugated sheet and foldable transversely thereto, the fly-sheet being extended to cover the flaps.

2. A wrapper for bottles and the like comprising a fly-sheet, a one-piece cushion sheet formed of single-faced corrugated board and

having the face thereof secured to the fly-
sheet, said cushion sheet and fly sheet being
adapted to extend around a bottle or other
article, and semicircular corrugated end
5 flaps integrally formed with the cushion
sheet and foldable transversely thereto, the
bottom and top of the fly-sheet being coter-

minous with the outer ends of the end flaps
and adapted to cover the flaps when the lat-
ter are in their folded position.

10

Signed at Chicago, Illinois, this 2nd day
of Feby, 1922.

EDWARD E. MASTON.
